AUTOMATIC GRINDING MACHINE

Herbert A. Silven, Worcester, Mass., assignor to
 Norton Company, Worcester, Mass., a corpora-
 tion of Massachusetts

Application October 4, 1937, Serial No. 167,131

17 Claims. (Cl. 51—105)

This invention relates to grinding machines, and more particularly to a full automatic grinding machine for grinding cylindrical work pieces.

One object of the invention is to provide a simple, thoroughly practical, improved full automatic grinding machine. Another object of the invention is to provide a hydraulically actuated full automatic grinding machine in which the various mechanisms are provided with safety interlocks. 10 A further object of the invention is to provide a full automatic hydraulically operated cylindrical grinding machine in which the various hydraulic control units are electrically interlocked. Another object of the invention is to provide an automatic work loading mechanism or carrier which is provided with a plurality of work receiving pockets simultaneously to grip the ground piece of work and a new piece of work and automatically and simultaneously to shift the ground 15 piece of work to a discharge chute and the new piece of work into alignment with the work supporting spindles.

A further object of the invention is to provide a work loading device in which a work carrying head or member is moved horizontally into position to grip a ground piece of work supported on the driving spindles and a new piece of work supported in a hopper and simultaneously to rock the carrier to transfer the ground piece of work 30 to a discharge position while the new piece of work is transferred from the hopper into alignment with the work supporting member. A further object of the invention is to provide a hydraulically actuated work loading mechanism in 35 which the work carrying element is hydraulically moved first in a horizontal direction to grip a ground piece of work and a new piece of work and then is hydraulically rocked to swing the carrier and thereby simultaneously to transfer the 40 ground piece of work from the spindles to a discharge position and the new piece of work from the hopper into alignment with the work supporting members.

Other objects will be in part obvious or in part 45 pointed out hereinafter.

The invention accordingly consists in the features of construction, combinations of elements, and arrangements of parts, as will be exemplified 50 in the structure to be hereinafter described, and the scope of the application of which will be indicated in the following claims.

In the accompanying drawings in which is 55 shown one of various possible embodiments of the mechanical features of this invention,

Fig. 1 is a front elevation of a grinding machine embodying this invention;

Fig. 2 is a piping and electrical diagram showing the electrical and fluid pressure connections between the various units and control valves;

Fig. 3 is a left hand end view of the left-hand work head, taken approximately on the line 3—3 of Fig. 1, on an enlarged scale, with the motor removed;

Fig. 4 is a horizontal sectional view through both of the work heads, taken approximately on the line 4—4 of Fig. 3;

Fig. 5 is a cross sectional view, on an enlarged scale, through the work feeding and discharging mechanism, taken approximately on the line 5—5 15 of Fig. 1, showing the work carrier in position during the grinding operation;

Fig. 6 is a similar view, showing the work carrier moved forward to grip a new work piece and the work piece which has been finish ground; 20

Fig. 7 is a similar sectional view through the work loading mechanism, showing the work carrier tipped to swing the ground piece of work into a discharge position and simultaneously to carry a new piece of work into alignment with the work 25 spindles;

Fig. 8 is a similar cross sectional view through the work loading mechanism showing the work carrier withdrawn to discharge a ground work piece in the discharge chute after the spindles 30 have gripped the work piece;

Fig. 9 is a detail view, on an enlarged scale, of the cycle trip switch;

Fig. 10 is a fragmentary cross sectional view, on an enlarged scale, taken approximately on the line 10—10 of Fig. 1;

Fig. 11 is a fragmentary longitudinal section, on an enlarged scale, taken approximately on the line 11—11 of Fig. 5;

Fig. 12 is a cross sectional view, taken approximately on the line 12—12 of Fig. 11;

Fig. 13 is a fragmentary cross sectional view, taken approximately on the line 13—13 of Fig. 11;

Fig. 14 is a fragmentary cross sectional view, taken approximately on the line 14—14 of Fig. 5; 45

Fig. 15 is a right-hand end elevation of the right-hand work head, on an enlarged scale, taken approximately on the line 15—15 of Fig. 1;

Fig. 16 is a rear view of the work loading mechanism, taken approximately on the line 16—16 of 50 Fig. 5; and

Fig. 17 is a horizontal sectional view, taken approximately on the line 17—17 of Fig. 16.

A full automatic grinding machine has been 55 illustrated in the drawings comprising a base

which supports a longitudinally adjustable table 21 on the usual flat way 22 and V way 23. To facilitate longitudinal adjustment of the table 21 relative to the base 20, the table 21 is provided with a depending rack bar 24 which meshes with a gear 25 (Figs. 1 and 10) mounted on the inner end of a rotatable shaft 26 which is journaled in a bearing 27 fixedly supported on the base 20. The outer end of the shaft 26 is provided with a squared-off portion 28 which is adapted to be engaged by a removable lever 29 so that the table may be adjusted longitudinally in setting up the machine for a given operation.

The base 20 also supports a transversely movable grinding wheel slide 32 which is supported on the usual V and flat ways to permit a transverse adjustment of the slide relative to the base. The slide 32 supports a rotatable wheel spindle 33 which in turn supports a rotatable grinding wheel 34. The grinding wheel spindle 33 may be rotated in any convenient manner such as, for example an overhead drive or a motor drive, such as an electric motor 35 mounted on the upper surface of the wheel slide 32. The motor 35 is provided with a driving pulley 36 which is preferably of a multiple V groove type and is arranged to transmit power by means of multiple V belts 37 to a multiple V groove pulley 38 mounted on the end of the wheel spindle 33 to rotate the grinding wheel 34 for a grinding operation.

The wheel slide 32 is arranged for a transverse feeding movement either manually for adjustment or setting-up of the machine, or automatically during the automatic cycle of operation thereof. The wheel slide 32 is provided with a depending half nut 40 which meshes with or engages a rotatable feed screw 41 journaled in a slidably mounted bearing 42 at one end and a bearing (not shown) at the other end. The forward end of the feed screw 41 is slidably keyed by means of a sleeve to the inner end of a rotatable shaft 43. The shaft 43 projects from the front of the machine base and is provided on its outer end with a gear 44 which meshes with a gear 45 supported on a shaft 46. A manually operable feed wheel 47 is also supported on the shaft 46 and is either formed integral with or fixedly mounted on the gear 45 so that rotation of the manually operable feed wheel 47 is transmitted through the gear 45 and the gear 44 to rotate the shaft 43 and thereby rotate the feed screw 41 in either direction to adjust the position of the wheel slide 32 as desired.

A pivotally mounted stop pawl 48 supported by a stud 49 is arranged to engage an abutment (not shown) positively to limit the infeed adjustment by the feed wheel 47. Associated with the feed wheel 47 is a micrometer adjusting mechanism 50 by means of which the abutment carried thereby may be precisely adjusted relatively to the feed wheel 47. This feed mechanism has not been illustrated in detail since it is not considered part of the present invention. For a more detailed disclosure of this feed mechanism, reference may be had to the expired United States patent to Norton No. 762,838 dated June 14, 1904 which discloses substantially the same type of feeding mechanism.

In order that the wheel slide 32 may be moved rapidly toward the work piece to grind the same automatically by the plunge-cut method, the feed screw 41 is connected through the bearing 42 with a piston rod 55. A fluid pressure cylinder 53 is arranged in axial alignment with the feed screw 41 and contains a slidably mounted piston

54 which is connected with the piston rod 55. A fluid pressure pump 59 which is driven by an electric motor or other suitable power drive serves to pump fluid through a pipe 60 from a reservoir 61 within the base 20. The pump 59 forces fluid under pressure through a pipe 62 to a main control or feed control valve 58. The main control valve 58 is preferably of a piston type comprising a valve stem 63 and a plurality of spaced pistons which form valve chambers 64, 10 65 and 66 therebetween. In the position of the valve 58 (Fig. 2), fluid under pressure enters the valve chamber 65 and passes out through a passage 67 into a cylinder chamber 57 to cause the piston 54 to move rapidly toward the left 15 (Fig. 2) to cause an infeeding movement of the wheel slide 32 and the grinding wheel 34. During the passage of fluid under pressure into the cylinder chamber 57, fluid is exhausted from a cylinder chamber 56, through a passage 68, into 20 the valve chamber 66, and out through a pipe 69 which exhausts into the reservoir 61.

The valve stem 63 is held in a forward feeding position (Fig. 2) by means of an electric solenoid 75 which is connected by a link 76 and a stud 77 25 to the lower end of a pivotally mounted lever 78 supported on a stud 79. The upper end of the lever 78 is connected by a pin or stud 80 with a spool shaped member 81 mounted on the outer end of the valve stem 63. When the solenoid 75 30 is energized, the valve 58 is held in position illustrated in Fig. 2. When the solenoid 75 is deenergized, the released compression of a spring 82 within the end of the valve casing serves to move the valve 58 quickly toward the right (Fig. 2) to reverse the position of the valve and to reverse the flow of fluid to and from the chambers 56 and 57 of the cylinder 53. The electrical apparatus for controlling the solenoid 75 will be described hereinafter.

Dash pot

The piston 54 and cylinder 53 mechanism, above described, serves to cause the grinding wheel 34 rapidly to approach or recede from the work piece. In order to reduce the rapid approaching movement to a predetermined grinding feed, it is desirable to provide a wheel feed regulator or controlling mechanism, such as a dash pot mechanism, which may be rendered effective when the grinding wheel 34 is about to contact 45 with the surface of the work piece being ground. As illustrated in Fig. 2, an outwardly projecting casing 85 is fixed to the head of the cylinder 53 and contains a pair of diametrically spaced dash 50 pot pistons 86 and 87. The dash pot pistons 86 55 and 87 normally are held in a rearward position by springs 88 and 89 respectively. During the rapid approach of the grinding wheel 34, the dash pot pistons are inoperative.

The piston rod 55 extends toward the rear of 60 the machine and is provided at its outer end with a sleeve 91 which may be adjusted longitudinally on a threaded portion 92 on the piston rod 55 and locked in adjusted position thereon by a lock nut 93. The parts are so arranged that the 65 sleeve 91 moves rearwardly when the piston rod 55 moves toward the rear. The dash pot pistons 86 and 87 are limited in their rearward movement by means of adjusting screws 94 and 95, respectively. When fluid under pressure is admitted to 70 the cylinder chamber 57 to cause the grinding wheel 34 to move toward the work piece, the rapid approaching movement thereof continues until the end of the sleeve 91 engages the ends 75 of the dash pot pistons 86 and 87, respectively.

The continued movement of the piston 54 toward the left (Fig. 2) is resisted by the dash pot pistons 86 and 87, respectively, which forces fluid under pressure from the dash pot chambers 97 and 98 into a reservoir 99. The dash pot chambers 97 and 98 are preferably interconnected with each other by the groove 102 and are arranged to exhaust fluid therefrom either through a needle valve 100 or an adjustable throttle valve 101 into the reservoir 99. The throttle valve 101 preferably is located on front of the machine Fig. 1.

Positive stop

In order to grind a work piece to a predetermined size, it is necessary to feed the grinding wheel 34 toward the work piece to grind the same and then to stop the infeed and allow the grinding wheel 34 to grind out or to allow the sparks to die out in order to round up the work so that it will be ground to a true cylindrical surface of a predetermined size. As illustrated in Fig. 2, the forward movement of the piston rod 55 causes a rapid approach until the sleeve 91 picks up the dash pot pistons 86 and 87 to cause a slow infeed which continues until an adjustable sleeve 104 engages a fixed surface 105 on the rear of the casing 85, thereby positively limiting the infeeding movement of the grinding wheel 34 and causing the wheel to dwell in contact with the work during the finish grinding period. The adjustable stop sleeve 104 surrounds the sleeve 91 and is held in adjusted position thereon by means of lock nuts 106.

The throttle valve 101 is connected by a pipe 108 with the reservoir 99. The pipe 108 also connects the reservoir 99 to a ball check valve 109 which remains closed during the forward feeding movement of the grinding wheel but which is opened upon the rearward movement of the grinding wheel 34 as the dash pot pistons 86 and 87 move to a rearward position to allow quick return of fluid to the dash pot chambers 97 and 98, respectively.

The dash pot mechanism is normally an independent fluid mechanism during the normal operation of the machine. In order readily to fill the reservoir 99 to maintain the desired quantity of fluid therein, a pipe 110 is connected between the pump 59 and reservoir 99. A valve 111 is located in the pipe 110 to control the flow of fluid through the pipe 110. An overflow pipe 112 is connected between the vertically extending portion of the reservoir 99 and the main reservoir 61 within the base 20 of the machine so that in case the fluid within the reservoir 99 rises above a desired level, the excess fluid will return directly to the reservoir within the base of the machine. Ordinarily the valve 111 is merely opened when it is desired to fill the reservoir 99 and then remains closed during the normal operation of the machine. If desired, however, in order to insure the fluid level within the reservoir 99 at all times, the valve 111 may be opened partially so that there will be a continuous flow of fluid into the reservoir 99, and in this case the overflow pipe 112 serves to prevent the fluid level rising above the desired point.

Work supporting and rotating mechanism

In order to grind the entire peripheral surface of a work piece automatically, it is desirable to provide means for supporting and driving the opposite ends of the work piece to center and support the work piece as well as to rotate it during the grinding operation. In the construction illustrated, a pair of spaced work supporting

heads 115 and 116 are mounted on a swivel table 119 which is provided on the work supporting table 21. The work heads 115 and 116 rotatably support a pair of aligned work supporting and rotating spindles 117 and 118, respectively. 5

The table 21 is provided with the usual swivel table 119 which is arranged to pivot on a central stud 120 set in the table 21 and projecting into a corresponding shaped aperture 121 in the swivel table 119. The upper surface of the swivel table 10 119 is formed with a dovetailed surface 122. The work head 115 is provided with a dovetailed surface 123 which mates with the surface 122 on the swivel table 119. A clamping block 124 held in position on the work head 115 by a clamping 15 screw 125 serves securely to lock the head 115 in position thereon. Similarly, the head 116 is provided with a dovetailed surface 126 which mates with the surface on the swivel table 119, and a clamping block 127 and clamping screw 128 securely clamp the work head 116 in position on the swivel table 119. 20

The spindles 117 and 118 are provided with a suitable driving mechanism so that they may be rotated in synchronism with each other so as to 25 provide a uniform timed driving of opposite ends of the work piece. In the construction illustrated an electric motor 134 is mounted on the left-hand end of the swivel table 119. The motor 134 is provided with a motor shaft 135 connected by a coupling 136 with a rotatable shaft 137 journaled in bearings 138 and 139 in the head 115. The shaft 137 carries at its inner end a gear 140 which meshes with a gear 141 mounted on the end of a rotatable shaft 142. 30 One end of the rotatable shaft 142 is journaled in a bearing 143 in the head 115 and the other end of the shaft 142 is journaled in a bearing 144 in the head 116. The shaft 142 is connected to simultaneously rotate the spindles 117 and 118, 40 respectively. A sprocket 145 is keyed on the left-hand end of the shaft 142 (Fig. 4) and is connected with a sprocket 146 on the work spindle 117 by means of a link chain 147. An adjustably mounted idler sprocket 148 serves to take up 45 any lost motion in the chain 147 and to maintain the chain in the desired driving tension.

Similarly, the other end of the shaft 142 is provided with a sprocket 150 which is connected with a sprocket 151 mounted on the rotatable work spindle 118 by means of a link chain 152. 50 An idler sprocket 153 serves to tension the link chain 152 as desired. By means of this driving mechanism, the work supporting and rotating spindles 117 and 118 may be rotated in synchronism with each other. 55

It is desirable to provide a suitable adjustment in the driving mechanism so that the two spindles having specially shaped work supporting and driving centers may be timed accurately with each other and thereafter rotated in absolute synchronism with each other. To accomplish this result, the sprocket 150 is not fixed to the shaft 142 but is rotatably supported thereon. A plate 155 is mounted on and fixed to a hub projecting from the sprocket 150. The plate 155 is mounted on and fixed to a hub projecting from the sprocket 150. The plate 155 supports a driving stud 156 which is arranged to drive a plate 157 which is fixedly fastened to the end of the drive shaft 142. The plate 157 is provided with a cut-out portion 158 which is of sufficient size and width to allow freedom of movement and adjustment of the stud 156 carried by the plate 155. The cut-out portion 158 provides a 60 65 70 75

pair of opposed adjusting screws 161 and 162 which are carried by the projections 159 and 160, respectively, on the plate 157 and serve to engage opposite sides of a squared end portion of the 5 stud 156. By slackening off on one of the screws 161 or 162 and tightening the other screw, the plate 155 may be adjusted angularly relative to the plate 157 so as to time the work supporting spindle 118 in the desired relationship with the 10 work supporting spindle 117.

In order to clamp or lock the plates 155 and 157 in adjusted position, a pair of clamping screws 163 and 164 are provided. These screws pass through elongated slots 165, 166 in the plates 15 157 and are screw threaded into the plate 155 so that the two plates may be rigidly locked in adjusted position when desired, thus permitting timing of the work spindles.

20 Work spindles

The two aligned opposed work supporting heads 115 and 116 are substantially identical in construction, the only difference being that one is a right-hand and the other a left-hand head. 25 Consequently, only one of these heads has been shown in detail in cross section. It should be understood, therefore, that the right-hand head (Fig. 3) is identical in construction and description with that described and illustrated in connection with the left-hand head. A collar 170 is threaded onto the end of the spindle 117 and contains a plurality of springs 171 which are arranged automatically to apply a tension to the parts of the anti-friction ball bearings 130 and 30 131 so that lost motion between the bearing parts is taken up at all times during the operation of the machine.

For convenience of assembly and manufacture, the spindle 117 is formed in two parts comprising the outer part 117 and an inner sleeve 172 which has a flange 173 engaging a correspondingly shaped aperture in the spindle 117. The other end of the sleeve 172 is threaded and a collar 176 fitted thereon serves to lock the spindle 117 and sleeve 172 so that they rotate together. A sleeve 175 is slidably keyed within the sleeve 172 by means of a key 176. The outer end of the sleeve 175 is provided with a tapered aperture adapted to receive the tapered portion of a work 45 supporting and driving center 177. A sleeve 178 within the sleeve 175 serves to locate a spring 179. The spring 179 is located between a flange on the sleeve 178 and a collar 180 which is screw threaded within the sleeve 172. The compression 50 of the spring 179 serves normally to hold the work supporting and driving center 177 and its supporting sleeve 175 toward the right (Fig. 3) into a driving position, as illustrated therein.

A fluid pressure cylinder 185 is formed either 55 integral or fixedly mounted on the end of the work head 115. The cylinder 185 contains a piston 186 which is slidably mounted therein and is normally held in a position toward the right, (Fig. 3) by two springs 187 to aid in moving and holding the work supporting center 177 in a direction toward the right to support and drive a work piece 188 having a plurality of broached splines therein.

To retract the center 177, fluid under pressure 60 may be admitted to a cylinder chamber 189 within the cylinder 185, which serves to cause the sleeve 175 to be moved toward the left (Fig. 3) against the compression of the spring 179.

The piston 186 is preferably connected with 65 the sleeve 178 by a lost motion connection, such

as by means of a flange 190 which is provided with an integral hub 191 that is connected to the sleeve 178 by a screw 192 having a cylindrical end portion thereon engaging an elongated slot in the sleeve 178. The flange 190 is positioned 5 within a recessed portion 193 in the left-hand end of the piston 186 and is located between the bottom of the recess 193 and a plate 194 which is fastened on the end of the piston 186. A collar 195 is fastened on the end of the sleeve 178 by 10 means of a screw 196. The collar 195 is provided with an adjusting screw 197 which is arranged parallel with the sleeve 178 and which serves to adjust the amount of lost motion between the piston 186 and the flange 190. The 15 piston 186 is arranged so that the sleeve 178 rotates therewithin and the lost motion connection between the piston and the sleeve 178 serves to allow the spindle to be rotated and the sleeve 178 to rotate freely without any friction between 20 the flange 190 and the piston 186. The springs 187 serve normally to hold the piston 186 in the position illustrated in Fig. 4, that is in a position toward the right, bearing against a thrust collar 198 which is fixedly mounted within and at one 25 end of the cylinder 185.

It will be readily apparent from the foregoing disclosure that the slidably mounted sleeve 175 within the work supporting spindle 117 is normally held in a position toward the right, that is, in operative position to support and drive a work piece 188 by means of the spring 179. The piston 186 is normally held in a position toward the right against the flanged portion 198 at the end of the cylinder 185 by means of the springs 30 187. When it is desired to retract the center 35 after a work piece 188 has been ground, fluid under pressure is admitted to the cylinder chamber 189 to move the piston 186 toward the left against the compression of the springs 187 and to retract the sleeve 175 toward the left against the compression of the spring 179 to withdraw the work supporting and rotating center 177 to an inoperative position. The fluid pressure system for controlling the admission of fluid to the 40 cylinder 185 will be hereinafter described.

Similarly, the right-hand head 116 (Fig. 3) is provided with a spindle and sleeve construction identical with that above described in connection with the left-hand head 115. The right-hand head 116 is provided with a cylinder 200 having a piston 201 slidably mounted therein. The piston 201 is normally held in the position illustrated in Fig. 3, up against a flange or thrust plate 202 (Fig. 4), fixed to the inner end of the 45 cylinder 200, by means of two springs 203. A lost motion connection is provided to connect the piston 201 to a sleeve 204 within the spindle 205. This lost motion connection comprises a flange 205 having a hub 206 formed integral 50 therewith. The flange 205 is located within a recess 207 within the piston 201 and the flange 205 is located between the bottom of the recess 207 and a plate 208 partially covering the end of the recess 207. The hub 206 is provided with a 55 screw 209 which has an inwardly projecting portion sliding within an elongated slot in the sleeve 204. A collar 210 is fixedly mounted on the end of the sleeve 204 by means of a screw 211 and is provided with an adjusting screw 212 arranged 60 to engage the flange 205 and adjust the position of the flange 205 relative to the sleeve 204 and thereby adjust the amount of lost motion between the flange 205 and the piston 201.

The spindle 118 is provided with an inner longi- 65

tudinally slidable sleeve 213 similar to the sleeve 175 in the work head 115, which in turn supports a work supporting and rotating center 214 similar to the center 177. The spindle 118 has 5 anti-friction ball bearings 132 and 133, similar to bearings 130 and 131 in the work head 115, and the take-up for lost motion is the same.

Since both of the work supporting centers 177 and 214 are arranged for endwise movement toward and from each other to grip and release a work piece 188 which is held thereon and therebetween for a grinding operation, it is desirable to provide suitable elements which may serve both to locate the work piece 188 in a predetermined 15 position with relation to the grinding wheel 34 and which also may serve as strippers to hold the work piece 188 against endwise movement during the withdrawal of the work centers 177 and 214. A sleeve 215 surrounds the slidable center supporting sleeve 213 on the work head 116. A flange 216 is formed integral with the sleeve 215 and is fixedly secured to rotate with the spindle 118. The end face of the sleeve 215 serves to locate the right-hand end of the work piece 188 when gripped between the supporting centers 177 and 214.

In order to compensate for any slight variations in the length of successive work pieces 188, a sleeve 217 surrounds the longitudinally adjustable sleeve 175 of the work head 115. The sleeve 217 is provided with an integral flange 218 which is fixedly mounted on the end of the spindle 117 to rotate therewith. In order to compensate for any slight variations in length of successive work pieces 188, a second sleeve 219 is slidably mounted within the sleeve 217 and is normally urged toward the right (Fig. 4) by means of equally spaced springs 220. A plurality of balls 221 arranged in spaced relationship are interposed between the sleeves 217 and 219 to allow the inner sleeve 219 to slide freely therewithin and also serve to drive the sleeve 219 with the sleeve 217. A band 222 mounted in a recess in the sleeve 217 maintains the balls 221 in driving position. The end face of the sleeve 219 engages the left-hand end of the work piece 188 (Figs. 4 and 11) and serves when the sleeves 175 and 213 are moved toward each other to grip a work piece 188 to move the work piece endwise so that its right-hand end engages the end of the sleeve 215. Due to the springs 220, the sleeve 219 may yield relative to the sleeve 217 to compensate for any slight variations in the length of successive work pieces 188.

The sleeves 215 and 219 also serve as strippers to hold the work piece 188 against endwise motion when the sleeves 175 and 213 are withdrawn to release a ground piece of work 188.

In order to hold the work supporting centers 177 and 214 in position within the sleeves 175 and 213, a rod 223 having a head 224 extends within the sleeve 178 and is screw threaded into the tapered portion of the center 177 so as to lock the center 177 in a definite operating position. Similarly, a rod 225 having a head 226 extends through the sleeve 204 and is screw threaded into the center 214 to lock the same in an operative position within the sleeve 213.

Work magazine or hopper

In a machine of this type, in order to make it fully automatic in its cycle of operation, it is desirable to provide a work feeding and discharging mechanism for automatically conveying successive work pieces into alignment with the opposed

work supporting and rotating centers 177 and 214, respectively, and similarly to discharge work therefrom after a grinding operation has been completed thereon. In order to reduce the idle time of the machine during the loading and unloading operation, it is desirable to provide a suitable work loading device whereby a new unground work piece 188 may be picked up from a magazine or hopper simultaneously with the gripping of the ground piece of work and the work loader then moved to shift the ground piece of work to a discharge position while moving the unground piece of work into alignment with the center, thereby unloading and loading the machine in a single movement of the work carrier or loader.

In the construction illustrated, a work hopper or magazine 227 carrying a plurality of unground pieces of work 188 is supported by the bracket 228 fixed to the work supporting heads 115 and 116 (Figs. 5 and 17). The outer end of 20 the work discharge chute 227 is similarly supported by an inverted V shaped supporting frame 229 which is adjustably connected to a bracket 230 which connects the heads 115 and 116. The frame 229 is provided with elongated slots through 25 which clamping bolts pass and which are arranged to clamp the frame 229 in adjusted position on the supporting bracket 230. By adjusting the frame 229 vertically, the angular position of the work magazine or hopper 227 may 30 be varied as desired so that the successive work pieces 188 will roll in succession into an operating position. The bracket 230 which connects the outer ends of the heads 115 and 116 is provided with an inwardly extending boss 231 (Figs. 35 3 and 5) which serves as a support for a pivot shaft 232 which passes through an aperture within the boss 231 and is held in adjusted position therein by means of a set screw 233.

A work carrier frame 235 is provided with a pair of spaced downwardly extending arms 236 (Fig. 1) which have enlarged hubs 237 and 238, respectively, at their lower ends, each of which is provided with a bushing or bearing member 239 and 240, respectively, which are pivotally supported on the non-rotatable shaft 232 and serve 45 to permit the work carrier frame 235 to be rocked about the shaft 232 as an axis.

The work carrier frame 235 is provided with a longitudinally extending fluid pressure cylinder 245. A piston 246 is slidably mounted within the cylinder 245. A piston rod 247 is formed integral with the piston 246 and passes through a cylinder head 248 having a fluid tight packing, which serves as a bearing support for the piston rod 247. A circular slide cover 249 is fastened on the outwardly projecting end of the piston rod 247 by means of a nut 250 threaded onto the end of the piston rod. A work carrier head 251 is fixedly mounted on the slide cover 249 so as to 55 move therewith. The work carrier head 251 is provided with a pair of spaced plates 254 and 255 (Fig. 16) having spaced pockets 252 and 253 formed therein which are of a diameter substantially equal to the piece of work 188 to be ground and are spaced apart by a distance substantially equal to the spacing between the piece of work 188a in the lower portion of the hopper 227 and the work piece 188, which is mounted on the centers 177 and 214 and has been ground to a 60 predetermined size.

In order to maintain the work carrying head 251 and its associated parts in a vertical position during the movement of the piston 246, a slide block 243 is fixedly attached to a slide cover 249 65

which surrounds the cylinder head 248. The slide block 243 is slidably supported on a cylindrical surface on the front end of the work carrier frame 235 and the cylinder head 248. The slide block 243 and the slabbed-off surface 244 on the frame 235 serve as a guide to maintain the work carrying head 251 in an operating position and prevent rotation thereof with the piston 246.

A pair of pivotally mounted spring actuating fingers 256 and 257 are provided on the work carrying head 251 which serve to hold a work piece 188 within the pockets 252 and 253 during the transfer movement from the magazine or hopper 227 to the work centers 177 and 214 and from the work centers to the discharge chute.

The fingers 256 and 257 are pivotally mounted on the upper part of the plates 254 and 255 of the work carrier head 251 by means of studs 258 and 259 to grip and hold the work piece 188a therein. Similarly, a pair of spring actuated trip fingers 260 and 261 are arranged on opposite sides of the lower part of the plates 254 and 255, respectively, and pivotally supported thereon by studs 262 and 263 and positioned to hold a finish 25 ground work piece 188 within the pockets 253 so as to transfer it to a discharge position.

The finger 256 is normally held in the position illustrated in Fig. 5 by means of a spring 265 which is connected between a stud 266 carried by the plate 254 and a stud 267 mounted on the finger 256. An adjustable stop screw 268 carried by the finger 256 together with a stop pin 269 mounted on the work carrier head 251 serves to limit the movement of the finger 256 in a counterclockwise direction.

The finger 257 is held in a similar position by means of a spring 272 which is fastened at one end to a stud 273 carried by the plate 255 and fastened at its other end to a stud 274 on the finger 257. An adjustable stop screw 275 carried by the finger 257 and a stop pin 276 serve normally to hold the finger 257 in position to support a work piece 188 in the pocket 252. The tension of the springs 265 and 272 is sufficient to hold a work piece 188 in the pocket 252 when the work carrier head 251 is moved forward and to withdraw the same from the hopper 227 when the work carrier 251 is swung to discharge a ground piece 188 and present a new piece of work 188a into alignment with the work centers 177 and 214.

The fingers 260 and 261 are similarly arranged, each having a spring 278 interposed between studs 279 on the plates 254 and 255 and a stud 280 on the upper surface of each of the fingers 260 and 261 normally tending to hold the fingers in the position illustrated in Fig. 5, with the adjustable stop screw 281 in engagement with a stop pin 282 carried by the plates 254 and 255.

The hopper 227, as illustrated, comprises a trough of a box-like cross sectional area having a portion of the top cut out. The inner cross-sectional area of the carrier is of sufficient size to allow a free rolling movement of the work pieces 188 as they are placed in the machine. The outer portion of the hopper 227 is arranged in an inclined manner so that the work pieces will roll toward the discharge end of the hopper. The first work piece 188a in the hopper 227 rests on a surface 285 at the lower end of the hopper 227 and is held in position therein by a pair of spaced pivotally mounted arms 286 and 287 which are pivotally mounted on studs 288 and 289, respectively (Fig. 16). The lower end of each arm 286 and 287 is provided with a screw 290 and 291

respectively, which project inwardly toward each other. The heads of the 290 and 291 screws serve to bear against the work piece 188a to hold the same within the hopper 227 until it is gripped and transferred therefrom by the forward and downward movement of the work carrying head 251. A spring 292 is interposed between the upper end of the lever 286 and a portion of the bracket 228 supporting the hopper 227 and serves normally to hold the lever 286 in the position illustrated in Fig. 5, with the head of the screw 290 engaging the work piece 188a. An adjustable stop screw 293 serves to limit the rocking movement of the lever 286 in a clockwise direction (Fig. 5) and similarly an adjustable stop screw 294 serves to limit the rocking movement of the arm 286 in a counterclockwise direction. The arm 287 is similarly mounted, so that a spring 295 normally rocks the lever 287 in a counterclockwise direction (Fig. 3) to maintain the screw 291 in position to support the work piece 188a in position with the work carrier pockets 252. An adjustable stop screw 296 carried by the lever 287 serves to limit the rocking movement of the lever in a counterclockwise direction, Fig. 3. Similarly, a stop screw 297 carried by the lever 287 serves to limit the rocking movement of the lever 287 under the influence of the spring 295 in a clockwise direction (Fig. 3). It will thus be seen that by means of the spring actuated, pivotally mounted levers 286 and 287, the heads of the screws 290 and 291 engaging the lower work piece 188a in the hopper 227 serve to retain the work piece in this position until the same is grasped by the pockets 252 on the forward movement of the work carrier head 251.

The work carrier head and associated parts, as shown in Fig. 5, are in a grinding position, that is the grinding wheel 34 is in engagement with the work 188 and the work is ground substantially to size. After completion of grinding on the work piece 188, the work carrier head 251 is preferably moved in a substantially horizontal plane so that the pockets 252 grip the work piece 188a and the pockets 253 grip the ground work piece 188. The work carrier 251 and its associated parts are moved forward to grip the ground work piece 188, as shown in Fig. 6. The work carrier head 251 and associated parts are then rocked about the shaft 232 as a pivot to swing the finished ground work piece 188 into position 188b (Fig. 7), in alignment with the upper end of a discharge chute 300 and at the same time swings the work piece 188a into position 188 in alignment with the work supporting and rotating centers 177 and 214. The work carrier 251 and its associated parts, while in a tilted position, are then withdrawn from the position shown in Fig. 7. As the work carrier head 251 recedes from the position in Fig. 7, a pair of lugs 301 and 302 on the discharge chute 300 engage the ground work piece 188b and hold it in the upper end of the discharge chute as the work head 251 recedes from the work. During this movement, the gripping fingers 260 and 261 are rocked about their studs 262 and 263 to release the work piece 188b from the pockets 253 into the discharge chute 300 whereupon the finished ground work piece 188 rolls by gravity to the pan 303 carried by the table 21 on the front of the machine. Excess coolant fluid is exhausted through the flexible hose 304 into the coolant reservoir in the base 20 of the machine.

Similarly, before the work carrier 251 starts its rearward movement, that is, toward the left 75

(Fig. 7), the work gripping centers 177 and 214 have gripped the work piece 188 and the withdrawal movement of the work carrier head 251 rocks the fingers 256 and 257 to withdraw the pockets 252 from engagement with the new piece of work 188 to be ground. The work carrier head 251 and its associated parts then assume the position illustrated in Fig. 8, after which the work carrier 251 and parts are rocked in a counter-clockwise direction to return into the normal position of the parts, as shown in Fig. 5, ready for the next cycle of movement thereof.

The movement of the work carrier 251 simultaneously to pick up a new piece of work 188a to be ground and the piece of work 188 which has been ground and simultaneously to shift them into an operating position and a discharge position, respectively, serves to reduce the idle movement and thereby increase the production and efficiency of the machine. The movement of the work carrier head 251 is preferably hydraulically actuated by means of a pair of pistons and cylinders, one of which moves the work carrier in a horizontal position and the other of which serves to rock the work carrier to transfer the work pieces, as above described. These two cylinders and pistons are interconnected so that they operate in timed relation with each other.

In the position of parts as shown in the diagram in Fig. 2, fluid under pressure, from the pump 59, passes through the pipe 62 into the chamber 65 of the valve 58 and passes out through a pipe 305, a section of which is flexible hose to allow free rocking of the work carrier frame 235, 30 through a passage 306 in a valve 307, through a pipe 308 and a valve 309 and a pipe or passage 310, into a cylinder chamber 311 within the cylinder 245 to move the piston 246 together with the piston rod 247 and plate 249 carrying the work carrying head 251 toward the left, (Figs. 2 and 40 5) to withdraw the work carrying head 251 into its rearward or inoperative position as shown. During the movement of the piston 246 toward the left, fluid within a cylinder chamber 312 45 exhausts through a pipe or passage 313 and a valve chamber 314 in the valve 307 and passes through a pipe 315, a section of which is flexible hose to allow free rocking of the work carrier frame 235 to the valve chamber 66 in the valve 58 and through the exhaust pipe 69 into the reservoir 61.

The valve 309 is adjusted to regulate the loading and discharging speed of the work carrying head 251 to time it with the movement of the work centers 177 and 214 and also to reduce the force of the blow of the piston 246 at each end of stroke to obtain smoothness and quietness of operation.

In order to rock the work carrying head 251 to move a work piece 188a from the hopper 227 into alignment with the work gripping centers 177 and 214, and to transfer a work piece 188 from the work centers to the discharge chute 300, a fluid pressure cylinder 316 is fixedly mounted on the outer end of the work carrier frame 235 and is arranged in a substantially vertical position, at right angles to the cylinder 245. The cylinder 316 contains a piston 317 which is connected by a piston rod 318 and a grooved spool shaped member 319 with a pair of opposed shoes 320 and 321 which engage the groove in the spool shaped member 319 and are pivotally supported by trunnions 322 and 323 on the bracket 230.

Fluid under pressure entering the cylinder chamber 311 passes through a passage 324 into a

cylinder chamber 325, which serves to produce a downward movement of the cylinder 316 and the work carrier frame 235, the piston 317 being held fixed to the bracket 230 to swing the work carrying frame 235 from the position illustrated in Fig. 8 into the position illustrated in Figs. 2 and 5. During the downward movement of the cylinder 316, fluid is exhausted from a cylinder chamber 326, through a pipe or passage 327, through radially extending holes 328 in the cylinder 245 and through longitudinally arranged holes 329, which extend to the circular groove which connect with the holes 328 within the piston 246. Fluid under pressure passing therethrough moves the collar 330, compressing a spring 331 and thereby allowing fluid passing through holes 329 to enter the cylinder chamber 312 and exhaust through pipe or passage 313, as above described. Normally the collar 330 seals the holes 329 when fluid is admitted into the chamber 312 to move the piston 246.

The valve 307 is normally inoperative and remains in the position illustrated in full lines in Fig. 2, except when it is desired to set up the work carrying head 251 and its associated mechanism when the same may be manually operated to move the work carrying head 251 independent of the other mechanisms of the machine.

When the wheel feed control valve 58 is shifted into its reverse position, the direction of flow of fluid under pressure to the cylinder 245 is changed so that fluid under pressure passes through the pipe 313 into the cylinder chamber 312 to cause the piston 246 to move toward the right (Figs. 2 and 5) so as to move the work carrying head 35 251 into the position illustrated in Fig. 6. The fluid in the cylinder chamber 325 is exhausted through the passage 324 into the radially extending holes 332 in the cylinder 245 through the longitudinally equally spaced holes 333 which extends to the continuous groove, and connects with the holes 332, within the piston 246, which moves the collar 334, compressing the spring 335, thereby allowing fluid passing through the holes 333 to enter the cylinder chamber 311 and exhaust through the pipe or passage 310, so as to move the work carrying head 251 into the position illustrated in Fig. 7, simultaneously transferring a ground piece of work 188 into the opening of the discharge chute 300 and transferring a new 50 piece of work 188a from the hopper 227 into alignment with the work gripping centers 177 and 214. As soon as the work centers have gripped the work 55 188, as hereinafter described, the feed valve 58 is again shifted, by energizing the solenoid 75, into the position illustrated in Fig. 2, in which position fluid under pressure causes a rearward movement of the work carrying head 251 into the position illustrated in Fig. 8, after which fluid is admitted to the cylinder chamber 325 again to rock the work carrier head 251 into the position illustrated in Figs. 2 and 5.

Electrical control and interlock

In a machine of this type, it is desirable to provide suitable interlocks between the various mechanisms of the machine to insure safe operation thereof, without endangering the operator or damaging the work pieces 188 passing therethrough. It is desirable to provide an electrical 65 interlock between the work gripping centers 177 and 214 and the wheel feed control valve 58 so that the solenoid 75 cannot be energized unless both of the work gripping centers are in an operative position in engagement with the work piece 75

188 to be ground. The mechanisms of the machine, as shown diagrammatically in Fig. 2, are in a grinding position. The trip switch 336 is normally held in a closed position by means of a spring 337. An actuating plunger 338 is arranged in the path of an adjustable screw 339 carried by a pivotally mounted lever 340 mounted on a stud 341 fixed to the end of the cylinder 185 of the work head 115. A rod 342 is fixed to the piston 186 and projects through an aperture within the end cover of the cylinder 185 and is arranged to engage the lever 340. A spring 343 having one of its ends connected to the upper end of the lever 340 and its other end connected to a stud 344 fixed to the top of the cylinder 185 serves normally to maintain the lever 340 in engagement with the rod 342. In the position of the parts shown, Fig. 2, the switch 336 is closed. When fluid under pressure is admitted to the cylinder chamber 189 to cause the piston 186 to move toward the left to withdraw the work centers 177 and 214 to an inoperative position, the rod 342 rocks the lever 340 in a counter-clockwise direction, which serves to move the switch actuating plunger 338 toward the left, Fig. 2, to trip the switch 336 and thereby break the circuit.

A similar safety connection including a normally closed trip switch 345 is normally held in a closed position by means of a spring 346. An actuating plunger 347 is arranged in the path of an adjustable screw 348 carried by a pivotally mounted lever 349 mounted on a stud 350 fixed to the end of the cylinder 200 of the work head 116. A rod 351 is fixed to the piston 201 and projects through an aperture within the end cover of the cylinder 200 and is arranged to engage the lever 349. A spring 352 having one of its ends connected to the upper end of the lever 349 and its other end connected to a stud 353 serves normally to maintain the lever 349 in engagement with the rod 351. In the position of the parts shown in Fig. 2, the switch 345 is closed. When fluid under pressure is admitted to the cylinder chamber 212 to cause the piston 201 to move toward the right (Fig. 2) to withdraw the work center 214 to an inoperative position, the rod 351 rocks the lever 349 in a clockwise direction which serves to move the switch actuating plunger 347 toward the right (Fig. 2) to trip the switch 345 and thereby break the circuit.

A similar trip switch 360 is operatively connected to be actuated by a cycle timing valve to be hereinafter described. The switch 360 is normally held in an open position by means of a spring 361 and is provided with an actuating plunger 362 which is arranged in the path of an adjustable screw 363 which is mounted in the upper end of a rock arm 364. The rock arm 364 is pivotally mounted on a stud 365. The lower end of the rock arm 364 is arranged to engage a plunger 366 which extends from and is formed integral with a piston 367 of a cycle timing cylinder 368.

Cycle timing piston and cylinder

The cycle timing piston and cylinder serves to control the admission of fluid under pressure to the work head actuating cylinders in timed relation with the other mechanisms of the machine. The piston 367 is normally held in a right-hand position (Fig. 2) by means of a pair of springs 369 and 370 which are connected between studs 371 and 372, respectively, on the cylinder cas-

ing and the other ends of which are fastened to studs 373 and 374 on the rock arm 364. These springs normally tend to rock the rock arm 364 in a counterclockwise direction. A cylinder chamber 375 within the valve 368 is connected by a pipe 376 with a passage 377 in a cycle timing valve 378. The passage 377 is connected by a ball check valve 379 with a passage 380 which enters a valve chamber 381 within the piston type cycle timing valve 378.

The pipe 376 leading from the cycle timing piston and cylinder 368 also connects with a pipe 382 which in turn is connected with an exhaust pipe 383 to exhaust fluid into the reservoir 61. A valve 384 is located in the pipe line 382 and serves to close off the exhaust from the cycle timing valve when desired in setting up the machine for grinding a given work piece 188. An adjustable throttle valve 385 is also located in the pipe line 382 and serves to adjust and control the rate of exhaust from the cycle timing piston and cylinder 368 and thereby to control the cycle of operation. When the fluid is exhausted from the chamber 375 in the cycle timing piston and cylinder 368 by the piston 367, the ball check valve 379 is closed by back pressure of the fluid so as to allow fluid to exhaust only through the pipe 376 to the needle valve 385 in the pipe line 382 to exhaust through the pipe 383.

Cycle timing valve

The cycle timing valve 378 is preferably a piston type valve comprising the valve pistons 386, 387, and 388 which are formed integral with a valve stem 389, thus forming valve chambers 390, 391, 392, and 393.

As shown in Fig. 2, fluid under pressure from the pump 59 passes through the pipe 62 and through a pipe 394 which connects with the valve 378. In the position of parts as shown, the valve piston 386 closes the port for the pipe 394. Fluid under pressure passing into the main control valve 58 passes out through a pipe 305 and through a pipe 395 and a throttle valve 396 into the valve chamber 390 to move the pilot valve to the right-hand position, as shown in Fig. 2. The valve 396 serves to control the rate of admission of fluid to the valve chamber 390 and thereby controls the rate of movement of the pilot valve. During this movement of the pilot valve, fluid within the chamber 393 exhausts through a pipe 397, an adjustable throttle valve 398 and a pipe 315 which exhausts fluid through the valve chamber 66 and returns it through the pipe 69 to the reservoir 61. The valves 396 and 398 serve to control the rate of movement of the cycle pilot valve.

When the main control valve 58 is reversed and fluid under pressure is admitted to the pilot valve chamber 393 to shift the pilot valve 378 toward the left, fluid under pressure passing through the pipe 394 may enter the valve chamber 381 and pass through the passage 380, the ball check valve 379, the passage 377, the pipe 376, into the cycle timing piston and cylinder 368 to cause the piston 367 to move toward the left, thereby rocking the rock arm 364 to move the switch plunger 362 toward the right (Fig. 2) which in turn closes the switch 360 so that the work spindles grip the next work piece, thereby closing trip switches 336 and 345, which closes the circuit and serves to energize the solenoid 75 to start the infeeding movement of the grinding wheel.

An adjustable stop screw 400 on the cycle timing valve 368 serves to limit the movement of the

piston 367 toward the left and thereby permits adjustment of the capacity of the cycle timing piston and cylinder so as to admit the desired amount of fluid to obtain the cycle of operation desired.

5 A push button 401 is provided in the electrical circuit to stop and start the cycle of operation. This switch 401 is connected in series with the normally closed trip switches 336, 345 and the 10 normally open trip switch 360.

The operation of this machine is readily apparent from the foregoing disclosure. When it is desired to start the machine in operation, a control button 402 on the front of the machine base 15 is actuated to start the wheel rotation, a push button 403 is actuated to start the fluid pump, and a push button 404 is actuated to start the work drive motor 134. The push button 401 is then actuated to start the cycle of operation. The 20 switch 401 is connected in series with the trip switches 336, 345, and 350, and serves to energize the solenoid 75 which shifts the control valve 58 into the position shown in Fig. 2 to start a forward feeding movement of the grinding wheel 34. As 25 summing a work piece to be already located on the work centers, fluid under pressure entering the valve chamber 65 passes into the pilot valve chamber 390 to shift the cycle timing valve 378 into the position illustrated in Fig. 2. The grinding wheel 34 advances to grind the work 188 to the required size and the extent of the grinding operation, that is infeed and dwell, is determined by the adjustment of the cycle timing piston and cylinder 368 which meters fluid from the valve 30

35 chamber 375 through the variable throttle valve 385 into the exhaust. When the cycle timing piston 367 has moved toward the right a sufficient distance during the grinding operation, the trip switch 360 is opened, thereby breaking the circuit 40 and deenergizing the solenoid 75 which releases the compression of the spring 82 and returns the feed control valve 58 to its reverse position so that fluid under pressure is admitted through the valve chamber 66 into the cylinder chamber 56 to 45 cause a rearward movement of the grinding wheel 34. The shifting of the feed control valve 58 admits fluid under pressure through the pipe 315 and the pipe 397 into pilot valve chamber 393 to start the cycle timing valve 378 moving toward the left and at the same time passes fluid 50 through the passage 314 in valve 307 and through the pipe 313 into the cylinder chamber 312 to move the work carrying member 251 forward simultaneously to grip a new piece of work 188a 55 and the ground-piece of work 188.

When fluid is admitted through the pipe 397 into the pilot valve chamber 393 to cause the timing valve 378 to move toward the left, fluid is also admitted from the pipe 397 into the pilot 60 valve chamber 392 and passes out through a pipe 410 which passes fluid through a passage 411 in a valve 412. Fluid entering the valve chamber 411 passes through a pipe 413 and a pipe 414 into the cylinder chamber 189 of the cylinder 185 and also 65 passes through a pipe 415 into the cylinder chamber 212 to cause the work gripping centers 177 and 214 to move away from each other out of gripping engagement with the work piece 188. The pressure is admitted to these cylinder chambers 189 and 212 only instantaneously while the timing valve 378 is being moved toward the left.

70 The speed of movement of the timing valve 378 as governed by the valves 396 and 398 is such as to allow time for the work centers 177 and 214 to be disengaged and the work carrier 251 to be

rocked to remove the finished work piece 188 and present an unground work piece 188a into alignment with the work centers 177 and 214 before the valve piston 388 covers the port to cut off fluid from the pipe 391. When the pressure from the pipe 391 is cut off and the pipe 419 is uncovered, the released compression of the springs 187 and 203, spring 179 in the work supporting head 115, and a similar spring in the work head 116 serves rapidly to move the work spindles simultaneously toward each other to engage the work centers 177 and 214 with the unground work piece 188a. This movement serves rapidly to exhaust fluid from the cylinder chambers 189 and 212 in the cylinders 185 and 200. Any leakage of fluid by the pistons 186 and 201 is exhausted by an extension of the pipe 383 into the reservoir 61. This movement of the spindles into an operative position serves to close the trip switches 336 and 345. The trip switch 360 being already 20 closed, thereby completes the circuit to energize the solenoid 75 to shift the feed control valve 58, so as to move the grinding wheel 34 toward the work piece 188. At the same time pressure in the pipe 305 passes through a passage 306 in a valve 307, through a pipe 308, the valve 309 and the pipe 310, into a cylinder chamber 311, to move the work carrier 251 away from the work into the position shown in Fig. 8. The radially extending holes 328 are uncovered and at the same time the holes 332 are uncovered and fluid passes through the passage 324 to the cylinder chamber 325 to rock the work carrier head 251 into the position illustrated in Figs. 2 and 5. During the downward movement of the cylinder 316, fluid is exhausted from the cylinder chamber 326 through the pipe 416, a ball check valve in cylinder 185, and through the pipe 414, the pipe 413, the valve 412, the pipe 410 and the pipe 419.

During the period while the work gripping centers are separated, a pipe 416 is uncovered by movement of the piston 186 toward the left (Fig. 2) which serves to admit fluid under pressure through a valve 417 and pipe or passage 327 into cylinder chamber 326 to move the cylinder 316 upwardly, thereby rocking the work carrier 251 in a clockwise direction to shift the ground piece of work 188 into a discharge position 188b and simultaneously to move a new piece of work 188a into axial alignment with the work 50 gripping centers.

The arrangement above described is such that the exhaust of fluid from the cylinder chamber 326 through the valve 417 is controlled in timed relation with movement of the pistons 186 and 201 which actuate the work gripping and rotating spindles. This arrangement of parts serves to delay applying of pressure of the work carrier against the work during its movement to transfer a ground piece of work to the discharge 60 chute and a fresh piece of work into axial alignment with the spindles. It also serves to eliminate the friction between the work carrying member and the work during the withdrawal of the work supporting centers.

If, however, it is desired to speed up the cycle of operation, the valve 417 may be closed and a valve 420 opened which allows passage of fluid between the cylinder chamber 326, the pipe 327 and the passage 328 in the work carrier horizontal cylinder. This connection avoids the delayed action of the work carrying member and tends to speed up the operation of the carrier.

The valve 412 is provided to facilitate independent movement of the work supporting cen-

ters in setting up and adjusting the machine elements. During the normal operation of the machine under control of the automatic cycle control mechanism, the valve 412 remains in the position illustrated in Fig. 2. If it is desired manually to operate the pistons independent of the cycle control mechanism, the valve 412 is shifted in a clockwise position into the position illustrated in dotted lines in Fig. 2 so that fluid under pressure from the pump 59 is admitted to the cylinder chambers 189 and 212, respectively, to withdraw the work supporting centers independently of the cycle control.

This cycle of operation is then continued on successive pieces of work. By manipulation of the various control valves, the timing of the movement of the various hydraulically actuated parts may be regulated as desired to obtain the desired coordination in the movement of the various parts of the machine.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:—

1. An automatic cylindrical grinding machine having a transversely movable rotatable grinding wheel, a pair of opposed axially aligned work supporting and rotating spindles, a work carrier to convey work pieces successively to said spindles each of which is operated by a separate fluid motor, a main control valve in control of said grinding wheel fluid motor and said work carrier fluid motor, a cycle timing valve controlled thereby, said cycle timing valve being in control of said spindle fluid motor, and a cycle timing piston and cylinder to control the cycle of operation.

2. An automatic cylindrical grinding machine having a transversely movable rotatable grinding wheel, a pair of opposed axially aligned work supporting and rotating spindles, a work carrier to convey work pieces to said spindles each of which is operated by a separate fluid motor, a main control valve in control of said grinding wheel and work carrier fluid motors, electrically operated means to actuate said valve to cause an infeeding movement of the grinding wheel, a cycle timing valve controlled by said valve, said cycle timing valve being in control of said spindle fluid motors, a cycle timing piston and cylinder to control the grinding cycle, and an electric switch actuated by said cycle timing cylinder to operate said electrical means to shift the main control valve and thereby cause a rearward separating movement of the grinding wheel.

3. An automatic cylindrical grinding machine having a transversely movable rotatable grinding wheel, a pair of opposed axially aligned work supporting and rotating spindles, means synchronously to rotate said spindles, means to rotate said grinding wheel, means to move said spindles simultaneously toward and from each other to grip or release a work piece therebetween, a wheel feeding mechanism arranged to feed the grinding wheel either toward or from the work, means including an electric solenoid to actuate said feeding mechanism to initiate an infeeding movement of the grinding wheel, and an elec-

trical interlock including trip switches actuated by the longitudinal movement of the work supporting spindles which are connected in series with said solenoid and are arranged to prevent energizing said solenoid until the work spindles are in supporting engagement with the work piece. 5

4. An automatic cylindrical grinding machine having a transversely movable rotatable grinding wheel, a pair of opposed axially aligned work supporting and rotating spindles, a work carrier to convey work pieces to said spindles each of which is operated by a separate fluid motor, a main control valve in control of said grinding wheel, an electric solenoid to actuate said valve to cause an infeeding movement of the grinding wheel, a cycle timing valve controlled by said valve, said cycle timing valve being in control of said spindle fluid motors, a cycle timing piston and cylinder to control the grinding cycle, and an electrical switch actuated by said cycle timing piston and cylinder to actuate said solenoid to shift the main control valve and thereby cause a rearward separating movement of the grinding wheel. 10 15 20

5. An automatic cylindrical grinding machine having a transversely movable rotatable grinding wheel, a pair of opposed axially aligned work supporting and rotating spindles, means synchronously to rotate said spindles, means to rotate said grinding wheel, means to move said spindles toward and from each other to grip a work piece therebetween, a grinding wheel feeding mechanism, means including a solenoid to initiate an infeeding movement of the grinding wheel, and an electrical interlock including trip switches actuated by the longitudinal movement of the work supporting spindles, said trip switches being connected in series with the solenoid so as to prevent actuation of the solenoid when the spindles are separated. 25 30 35 40

6. An automatic cylindrical grinding machine having a transversely movable rotatable grinding wheel, a pair of opposed axially aligned work supporting and rotating spindles, a work carrier to convey work pieces to said spindles each of which is operated by a separate fluid motor, a main control valve in control of said grinding wheel and work carrier fluid motors, an electric solenoid to move said valve in one direction to cause an infeeding movement of the grinding wheel, a cycle timing valve controlled by said valve, said cycle timing valve being in control of said spindle fluid motors, a trip switch associated with said spindles and arranged to be actuated when said spindles are separated, a cycle timing piston and cylinder to control the grinding cycle, an electric switch actuated by said cycle timing piston and cylinder, and electrical connections between said trip switches, said electrically operated switch and solenoid, whereby the solenoid is rendered inoperative when the spindles are separated. 45 50 55 60

7. An automatic cylindrical grinding machine having a transversely movable rotatable grinding wheel, a pair of opposed axially aligned work supporting and rotating spindles, a work carrier to convey work pieces to said spindles each of which is operated by a separate fluid motor, a main control valve in control of said grinding wheel and work carrier fluid motors, an electric solenoid to actuate said valve to cause an infeeding movement of the grinding wheel, a cycle timing valve controlled by said valve, said cycle timing valve being in control of said spindle fluid motors, a cycle timing piston and cylinder opera- 70 75

tively connected with said valves and arranged to control the grinding cycle, an electric switch associated with each of said spindles, connections between said switches and spindles whereby the 5 switches are actuated when the spindles are separated, and electrical connections connecting the trip switches and solenoid in series so as to prevent actuation of the main control valve while the spindles are separated.

10. An automatic cylindrical grinding machine having a transversely movable rotatable grinding wheel, a pair of opposed axially aligned work supporting and rotating spindles, a work carrier to convey work pieces to said spindles each of which 15 is operated by a separate fluid motor, a main control valve in control of said grinding wheel and work carrier fluid motors, an electric solenoid to actuate said valve to cause an infeeding movement of the grinding wheel, a cycle timing 20 valve controlled by said valve, said cycle timing valve being in control of said spindle fluid motors, a cycle timing piston and cylinder operatively connected with said valves and arranged to control the grinding cycle, an electric switch associated 25 with said spindles, connections between said switch and spindles whereby the switch is actuated when the spindles are separated, an electric switch which is actuated by said spindles, an electric switch actuated by said cycle timing piston 30 and cylinder, and electrical connections connecting said switches and solenoid in series with each other so as to prevent shifting of the main control valve and an infeeding movement of the grinding wheel when the work spindles are separated.

35. An automatic cylindrical grinding machine having a transversely movable rotatable grinding wheel, a piston and cylinder to move said wheel in either direction, a pair of opposed aligned rotatable work supporting spindles, means synchronously to rotate said spindles, means including a fluid pressure piston and cylinder operatively connected to each of said spindles and arranged to move the same toward and from each other to grip a work piece therebetween, a pivotally mounted transversely movable work carrier, a hopper associated therewith, a fluid pressure piston and cylinder to move said carrier transversely, a fluid pressure piston and cylinder operatively connected to rock said carrier, a main 40 control valve operatively connected to control the admission of fluid to said wheel feed cylinder and said work carrier cylinders, and a cycle timing valve operatively connected with said main control valve and arranged to control the admission and exhaust of fluid from said work 45 spindle cylinders.

45. An automatic cylindrical grinding machine comprising a transversely movable rotatable grinding wheel, means including a piston and cylinder to move said wheel transversely, a pair of opposed aligned rotatable work supporting spindles, means including an electric motor synchronously to rotate said spindles, a fluid pressure piston and cylinder operatively connected to move each of said spindles, a work receiving hopper, a discharge chute, a pivotally mounted transversely movable work carrier having two work receiving pockets thereon, means including a piston and cylinder to move said carrier transversely simultaneously to grip a new piece of work and a ground piece of work supported on said spindles, means including a fluid pressure piston and cylinder to rock said carrier simultaneously to convey the ground work piece to the discharge chute and to convey the new work piece into axial alignment with the work spindles, and a main control valve operatively connected to control the admission of fluid to the grinding wheel cylinder, the work spindle cylinders and the work carrier cylinders so that the various elements are moved in timed relation with each other.

50. An automatic grinding machine comprising a transversely movable rotatable grinding wheel, means including a piston and cylinder to move said wheel transversely, a pair of opposed aligned rotatable work supporting spindles, means including an electric motor synchronously to rotate said spindles, a fluid pressure piston and cylinder operatively connected to move each 5 of said spindles, a work receiving hopper, a discharge chute, a pivotally mounted transversely movable work carrier having two work receiving pockets thereon, means including a piston and cylinder to move said carrier transversely simultaneously to grip a new piece of work and a ground piece of work supported on said spindles, means including a fluid pressure piston and cylinder to rock said carrier simultaneously to convey the ground work piece to the discharge 10 chute and to convey the new work piece into axial alignment with the work spindles, and connections between said spindle cylinders and said work carrier cylinders whereby the rocking of the work carrier is interlocked with the work 15 spindles so that the carrier is held against rocking movement while the spindles are separated.

55. An automatic cylindrical grinding machine, a work loading device having a pivotally mounted transversely movable work carrier head 20 thereon, a pair of spaced work receiving pockets on said head, means including a fluid pressure operated piston and cylinder to move said head transversely into an operating position, and means including a fluid pressure piston and cylinder 25 operatively connected thereafter to rock said work carrier head into a second operating position.

60. An automatic cylindrical grinding machine, a work loading device having a pivotally mounted, transversely movable work carrier head, a pair of spaced work receiving pockets on said head, means including a piston and cylinder to move said head transversely into an operating position, means including a second piston and cylinder to rock said head into a second 40 operating position, and fluid pressure means including a control valve mechanism operatively connected to said cylinder so as to first cause a transverse movement of said head, then a rocking movement of said head, then a transverse movement of said head in the reverse direction, and a rocking movement of said head in the opposite direction.

65. An automatic cylindrical grinding machine having a pair of opposed axially aligned work supporting and rotating spindles, a work hopper, a work loading device comprising a pivotally mounted transversely movable work head thereon having a pair of spaced work receiving pockets simultaneously to grip an unground and a ground work piece, a discharge chute, means including a piston and cylinder to move said head transversely simultaneously to grip an unground work piece supported in said hopper and a ground work piece supported on said spindles, and means including a piston and cylinder to rock said head so as to shift the unground work piece into alignment with said spindles and to 70 convey the ground work piece to the discharge chute 75.

shift the ground work piece into said discharge chute.

15. In an automatic cylindrical grinding machine having a pair of opposed axially aligned work supporting and rotating spindles, means including a fluid pressure piston and cylinder operatively connected to move said spindles toward and from each other, a work hopper, a work loading mechanism comprising a pivotally mounted transversely movable work carrier head, a pair of spaced work receiving pockets on said head, means including a piston and cylinder to move said head transversely simultaneously to grip a new work piece supported in said hopper and a ground piece of work supported on said spindles, means including a piston and cylinder to rock said head so as to discharge the ground piece of work and to present a new piece of work into axial alignment with the work supporting spindles, and a hydraulic interlock between said spindle actuating cylinders and said work carrier rocking cylinder whereby said latter cylinder is rendered inoperative until the work spindles have separated to release a ground piece of work.
16. In an automatic cylindrical grinding machine having a pair of opposed aligned work supporting and rotating spindles, a fluid pressure piston and cylinder operatively connected to each of said spindles and arranged to cause them to approach or recede from each other, means synchronously to rotate said spindles, a work hopper, a discharge chute, a work loading device comprising a pivotally mounted transversely movable work carrier head thereon, a pair of spaced work receiving pockets on said head, means including a piston and cylinder to move said head trans-

versely simultaneously to grip a work piece supported in said hopper and a ground piece of work supported on said spindles, means including a piston and cylinder to rock said head so as to simultaneously transfer said work pieces, and fluid pressure connections between one of said spindle cylinders and said work head rocking cylinder whereby said rocking cylinder is rendered inoperative until said work spindles have moved to an inoperative position.

17. In an automatic cylindrical grinding machine, a pair of opposed axially aligned work supporting and rotating spindles, means synchronously to rotate said spindles, means including a piston and cylinder to move each of said spindles toward and from each other, a work hopper, a discharge chute, a work loading device including a pivotally mounted transversely movable work carrier head, means including a piston and cylinder to rock said head so as to shift the work pieces simultaneously into alignment with said spindles and said discharge chute respectively, a main control valve to admit fluid to said first cylinder to move said work carrier head transversely, a cycle timing valve actuated by said main control valve, connections between said cycle timing valve and said spindle actuating cylinders to control the movement of said spindles in timed relation with the movement of said work head, and fluid pressure connections between one of said spindle cylinders and said work head rocking cylinder which are arranged to render said work head rocking cylinder inoperative until the work spindles have separated and moved to an inoperative position.

HERBERT A. SILVEN.
